**MIXING AND DISPENSING APPARATUS
FOR POISON SPRAY**
Frederick M. Gleckler, Cherry Hill, N.J.
(R.D. 1, Ridgely, Md. 21660)
Filed July 12, 1967, Ser. No. 652,939
7 Claims. (Cl. 259—2)

ABSTRACT OF THE DISCLOSURE

An apparatus for use in safely mixing poison spray, having a pump for supplying the mixture from a mixing container to a spray head for spraying field crops and orchards. A blower and filter carries off and collects spray dust and fumes from the mixing container, during the mixing operation, to protect workmen in the vicinity of the apparatus. The pump and blower are connected to the container above the liquid level therein during the mixing of the spray. The container is rotated to locate the pump connection adjacent a bottom part of the container for dispensing the spray.

Background of the invention

This invention relates to the art of mixing and dispensing poison spray liquids, especially insecticides.

The prior art includes devices which may be utilized for mixing and thereafter dispensing liquid insecticides, but which include no means for protecting workmen in the vicinity of the apparatus.

Summary

A primary object of the present invention is to provide an apparatus in which poison sprays can be mixed with a maximum safety to workers in the vicinity of the apparatus.

More particularly, it is an object of the invention to provide means for removing and collecting poison spray dust and fumes during the mixing operation.

Another object of the invention is to provide a mixing and dispensing apparatus including a receptacle in which the poison material is mixed with a liquid, and which includes a pump which is disposed above the level of the contents of the container during the mixing operation to prevent clogging of the pump.

Another object of the invention is to provide a mixing container capable of being rotated about its horizontal axis to locate the pump adjacent the bottom of the container, after the mixing operation has been accomplished, and so that the poison spray mixture can be dispensed from the container by the pump to a spray head or other discharge outlet.

Various other objects and advantages of the invention will hereinafter become more fully apparent from the following description of the drawings illustrating a presently preferred embodiment thereof, and wherein:

Brief description of the drawings

FIGURE 1 is a side elevational view, partly broken away, illustrating the complete apparatus;

FIGURE 2 is an end elevational view looking from right to left of FIGURE 1;

FIGURE 3 is a view corresponding to FIGURE 2 but showing the container rotated about its horizontal axis to a dispensing position;

FIGURE 4 is a fragmentary side elevational view looking in the opposite direction to FIGURE 1;

FIGURE 5 is a cross sectional view taken substantially along a plane as indicated by the line 5—5 of FIGURE 4;

2

FIGURE 6 is a fragmentary longitudinal sectional view taken substantially along a plane as indicated by the line 6—6 of FIGURE 2; and

FIGURE 7 is a fragmentary end elevational view of a part of the apparatus, looking from left to right of FIGURE 1.

Description of the preferred embodiment

Referring more specifically to the drawings, the mixing and dispensing apparatus in its entirety is designated generally 10 and includes an elongated cylindrical container 11 which is disposed with its horizontal axis in substantially a horizontal position and with a portion of its cylindrical side wall 12 resting upon a suitable horizontal supporting surface 13. One end wall 14 of the container 11 is provided with a segmental shaped opening 15 preferably constituting approximately one-fourth of the area of said wall, as best seen in FIGURE 5.

A rigid angular conduit 16 has one end secured in the side wall 12 and communicating with the interior 17 of the container 11. The other upturned end of the conduit 16 is connected to the inlet 18 of a conventional electric pump 19 which is supported by the conduit 16 at the side of the container 11. A hose 20 constituting the outlet of the pump 19 leads to any discharge device, not shown, such as a conventional spray head. A drainage opening 21 is formed in the side wall 12, preferably in the same horizontal plane as the connection of the conduit 16 thereto, as best seen in FIGURE 6, and is normally closed by a threaded plug 22.

A rigid angular conduit 23 has one end extending through and secured in the other end wall 24 of the container 11. The other upturned end of the conduit is connected to the inlet 25 of a centrifugal blower 26 which is supported by said conduit 23, and which in turn supports an electric motor 27 of said blower. A hose 28 extends from the outlet 29 of the blower 26 and discharged into one side of a box or receptacle 30 which has one or more filter outlets 31 in the opposite side thereof, as seen in FIGURE 7.

The pump 19 may be connected by wiring 32 to any suitable source of electric current, such as a storage battery 33, and the motor 27 may be connected to the same current source 33 by wiring 34. A switch 35 is interposed in the wiring 32 and a switch 36 is interposed in the wiring 34.

With the apparatus in the position as illustrated in FIGURES 1 and 2, the container 11 is filled with a liquid, usually water, up to the level as indicated by the broken line 37 in FIGURE 5, through the opening 15, which is disposed above said liquid level line. The switch 36 is then closed for energizing the motor 27 to operate the blower 26. The poison spray material, usually in powdered form is then introduced into the chamber 17 through the opening 15 to be mixed with the liquid. During the mixing operation dust and fumes from the spray material will be extracted from the chamber 17 through the conduit 23 by the blower 26 and discharged through the hose 28 into the box 30 where said dust and fumes will be collected. The purified air will be separated from the dust and fumes and will escape from the box 30 through the filters 31. As seen in FIGURE 6, the conduit 23 is located above the liquid level 37 in the mixing position of the container 11, as seen in FIGURES 2 and 6, and is also located above the liquid level in the dispensing position of the container 11, as seen in FIGURE 3. Likewise, as seen in FIGURE 6, the connection of the conduit 16 to the container 11 and the drain opening 21 are disposed above the liquid level 37 in the mixing position of the container, so that the conduits 16 and 23, the pump 19 and blower 26, and the drainage opening 21 will

not be clogged by the spray material during the mixing operation.

After the mixing operation has been completed, the switch 36 is returned to an opened position to de-energize the motor 27 and the container 11 is rotated counter-clockwise about its horizontal axis from its position of FIGURE 2 to its dispensing position of FIGURE 3 in which the conduit 16 and pump 19 are located near the bottom of the container 11. The switch 35 is then closed for completing the electric circuit to the pump 19 so that the mixture can be dispensed by said pump from the chamber 17 through the conduit 16 and hose 20 to a spray head or other discharge device, not shown.

Various modifications and changes are contemplated and may be resorted to, without departing from the function or scope of the invention as hereinafter defined by the appended claims.

I claim as my invention:

1. A mixing and dispensing apparatus comprising a container mounted for rotation about its horizontal axis, said container having an end wall provided with an opening for partially filling the container in a first position thereof with a liquid and a material to be mixed with the liquid and in which first position the material and liquid are mixed, said container having a side wall, a rigid conduit having one end secured in said side wall and opening into the container, a pump having an inlet secured to the other end of the conduit and supported thereby, and a discharge conduit leading from the outlet of said pump, said opening and first conduit end being disposed above the level of the mixture in said first position of the container, and said container being rotatable in one direction about its horizontal axis to position said conduit adjacent the bottom of the container in a second position thereof for pumping the mixture therefrom, said opening being disposed above the mixture level in said second position of the container.

2. A mixing and dispensing apparatus as in claim 1,

said material comprising a poison, a second rigid conduit having one end secured in the other end wall of said container and communicating with the interior thereof, a blower connected to the other end of said second conduit, a conduit leading from the outlet of said blower, and means into which said last mentioned conduit discharges for collecting spray dust and fumes from the container during the mixing operation.

3. A mixing and dispensing apparatus as in claim 2, said first mentioned end of the second conduit being disposed above the mixture level in said container in both positions of the container.

4. A mixing and dispensing apparatus as in claim 2, said pump comprising an electric pump, an electric motor for driving said blower, and electric circuits each including a switch connecting the pump and blower motor to a source of electric current for selectively operating the pump and blower.

5. A mixing and dispensing apparatus as in claim 2, said first and second mentioned conduits having upturned ends to which the pump and blower, respectively, are connected.

6. A mixing and dispensing apparatus as in claim 2, said means comprising a box having a filter covered outlet for trapping the spray dust and fumes therein and for permitting the escape therefrom of purified air.

7. A mixing and dispensing apparatus as in claim 1, said side wall having a normally sealed drainage opening disposed in the same horizontal plane as the first mentioned end of said first mentioned conduit.
